(57) **CLAIM**

The ornamental design for a polishing pad, as shown and described.

DESCRIPTION

FIG. 1 is a bottom perspective view of a polishing pad showing my new design;

FIG. 2 is a top perspective view thereof;

FIG. 3 is a top plan view thereof;

FIG. 4 is a bottom plan view thereof;

FIG. 5 is a right-side view thereof; and,

FIG. 6 is a cross-sectional view of the polishing pad taken in the direction of line 6-6 shown in FIG. 4.

The left-side view, front view and back view are identical to the right-side view shown in FIG. 5.

1 Claim, 3 Drawing Sheets
